UNITED STATES PATENT OFFICE

FRANK DITCHFIELD, OF CLEVELAND, OHIO, ASSIGNOR TO THE YOUNGSTOWN STEEL DOOR COMPANY, OF CLEVELAND, OHIO, A CORPORATION OF OHIO

DOOR LOCK AND OPERATOR

Application filed April 28, 1928. Serial No. 273,477.

This invention relates to improvements in door lock and operator, and, more specifically, to such a door lock and operator as is particularly adapted for horizontally slideable doors of the box car type.

One object of the invention is to provide a door lock and operator of the lever type wherein relatively high leverage is effective in the most efficient manner for forcing the door during the last part of its closing movement and during the initial part of its opening movement.

Another object of the invention is to provide a combined locking and operating device including a hasp so arranged that the hasp may be readily pried off of its staple by the operating element so as to facilitate opening of the door in the event of binding between the hasp and its staple.

Another object of the invention is to provide a combined lock and operator of the type above indicated wherein the locking means and the operator proper may be applied as a single unit.

Other objects of the invention will more clearly appear from the description and claims hereinafter following.

In the drawings forming a part of this specification, Fig. 1 is an elevational view of a portion of a box car showing my improvements applied to the side door thereof. Fig. 2 is a vertical sectional view corresponding to the line 2—2 of Fig. 1. In this figure, the dotted line position of the lever indicates the position assumed when releasing the hasp from its staple. Fig. 3 is a horizontal sectional view corresponding to the line 3—3 of Fig. 1. Fig. 4 is a detail vertical sectional view of the locking means corresponding to the line 4—4 of Fig. 1. And Figs. 5 and 6 are views corresponding to Figs. 1 and 2, respectively, showing another embodiment of the invention.

Referring first to the construction illustrated in Figs. 1 to 4, inclusive, the side wall of the box car is indicated at 10, the same having a door opening defined in part by a front door post 11, said opening being adapted to be closed by a door 13. The door which I have chosen for illustration is of the sheet metal

type, the details of the front edge of which are illustrated best in Fig. 3 but which, per se, do not constitute any part of this invention. As shown, said door includes a plurality of horizontally extending corrugations, to one of which—14—is secured the hasp fastener 15, the latter having a loop 16 at its forward end, the loop in turn having a hook end 17 that is entered through an opening in the ridge of the vertically extending corrugation 18 of the door and by which the fastener is effectively interlocked with the door.

In carrying out my invention, I employ a hasp designated generally by the reference character A; a locking means indicated generally by the reference character B; and an operator C.

The hasp A is pivotally connected to the loop 16 of the fastener above referred to, said hasp A being relatively elongated and having an arcuate end 19 normally extending upwardly and the free end of which has an opening or recess 20 for the purpose hereinafter described. Intermediate its ends, the hasp or link A has a longitudinally extending opening 21 adapting the hasp to be positioned over the staple 22 of the locking device proper B. Said staple 22 is preferably formed integrally with a casting having a base section or web 23, an outwardly offset web or housing section 24 and a laterally extended flange 25. Said casting is secured to the car side by any suitable means such as rivets or bolts indicated at 26. The outwardly offset housing or web 24 has a vertically elongated slot 27 therein in which is suitably mounted a lateral extension 28 on the locking pin 29. Said extension 28 has a head 30 at its inner end, as shown in Fig. 4, thereby preventing the locking pin 29 from becoming disassociated from the securing casting when the latter is in place on the car side. The pin 29 has its lower end 31 adapted to enter a slot 32 provided in the staple 22 on the outer side of the hasp A when the latter is in locked position.

The pin 29 is also preferably provided with a lateral extension 33 which is positioned closely adjacent the staple 22 when the locking pin is in operative position, said projection 33 having a small opening or recess

34 therein aligned with the opening 32 in the staple and adapted to receive the band of the usual type of railroad seal.

In the form shown in Figs. 1 to 4, the lateral extension 25 of the mounting plate is formed with an integral boss or fulcrum 35 projecting horizontally outwardly therefrom, as shown in Fig. 2. The operating lever C is loosely pivotally mounted on said boss, as shown in said Fig. 2, the opening 36 in the lever for this purpose being preferably outwardly flared, as shown in Fig. 2. At its upper end, the lever C has a relatively short extension or bar 37 which may be slightly rounded, as indicated at 38, the rounded edge forming a fulcrum for the lever C when the lower or handled end 39 thereof is pulled outwardly, as shown by dotted lines in Fig. 2. In this operation of the lever C, the lateral extension plate 25 serves as the bearing for the lever in any angularly adjusted position that the latter may assume, as shown in Fig. 1. The lever C is retained on the boss 35 by any suitable means, such as the washer 40 and rivet 41.

Intermediate the point of its pivotal support and the handle end proper, the lever C is provided with an outwardly projecting rounded lug 42 having a somewhat enlarged flange 43 at its outer end. Said lug 42 is of such size as to enter the opening or recess 20 in the hasp A and, after being entered, the flange 43 will slightly overlie the surface of the hasp or link A and prevent accidental disengagement.

Assuming the parts in the position shown in full lines in Fig. 1, my improvements are utilized as follows. After breaking the train seal, the locking pin 29 is lifted vertically so as to be disengaged from the staple 22. It frequently happens that the hasp binds very tightly on its staple, due to slight shifting of the door or weaving of the car parts while in motion and it has heretofore been difficult, at times, to properly release the ordinary hasp from its staple. With my improvements, any such difficulty is easily overcome by the operator merely pulling the lever C outwardly at its lower end to a position such as indicated by the dotted lines in Fig. 2. Ample leverage is thus provided to forcibly loosen the hasp or link A from the staple 22. After the hasp has thus been disengaged from its staple, the lever C is swung to the dotted line position in Fig. 1 so as to bring the stud 42 thereon opposite the opening 20 in the link, whereupon the free end of the link is applied over the lug 42, as will be understood. The lever C is then swung in a counter-clockwise direction, thus forcibly starting the door in an opening direction. Attention is called to the fact that the hasp or link A is so curved at its free end and the lug 42 is so located on the lever C that the line of applied force 65 from the lever C will be directly, or substan-

tially directly, horizontally in line with the point of attachment between the hasp and the door, thus obtaining the most effective application of the force to the opening of the door at the beginning of the opening movement, at which time the greatest force is desirable. After the door has been partially opened, the lever and hasp are disengaged, as will be understood. The final closing of the door is accomplished by the hasp A and lever C by detachably locking the same and swinging the lever C to the left, or clockwise, as will be understood. In the locked condition of the parts, it will be observed that the pin 29 locks the hasp A and the latter in turn overlies the lever C so that it cannot swing outwardly from the car side. It will further be observed that all parts of my improved combination, with the exception of the hasp proper, are adapted to be applied to the car side as a unit, thus not only minimizing the cost of labor but assuring proper relationship of the lever to the locking device proper and hence with respect to the hasp when it is brought into play.

Referring next to the form of the invention shown in Fig. 5, the arrangement of door retainer, hasp and locking device is the same as in the first described form. The only differences are with respect to the mounting of the operating lever D. In this form, the base plate of the locking device has a lateral extension or web 125. To mount the lever D a somewhat different arrangement is provided. From the web 125 is outwardly extended a hub or journal 135 on which is freely rotatably mounted a special hanger or support 60, the latter having an upwardly projecting radial flange 61 and a shorter downwardly extending flange 62. Said hanger is held in place by a washer 140 and rivet 141. The lever D, at its upper end, has a loop section providing two side arms 63—63 which straddle the flange 61 and by which the lever is pivotally connected to the latter through a pivot-forming rivet 64. Below the pivot 64, the loop is widened as indicated at 65—65 so as to surround the hanger 60 and also clear the washer 140. The lever is also suitably notched as indicated at 66 to receive the downwardly projecting flange 62 of the hanger so that, when the lever D is swung in a plane parallel to the car side, a substantial interlock is provided between the lever proper and its support or hanger.

In the embodiment just described, it is evident that the lever D is swingable about one axis for forcing the door open through the hasp or link A and to close the door, the same as in the preceding form described. Similarly, the lever D is swingable outwardly so as to release the hasp from its staple, this movement being about the pivot 64, as clearly illustrated by the dotted line position of the parts in Fig. 6.

I have herein shown and described what I now consider the preferred manner of carrying out my invention, but the same is merely illustrative and I contemplate all changes and modifications that come within the scope of the claims appended hereto.

I claim:

1. In a device of the character described for sliding doors, in combination: A link; a lock for said link; and an operating lever, the latter being mounted for movement about two different axes, whereby, when swung about one axis, the same is cooperable with the link to force it in a plane parallel to the door and, when swung about its other axis, is cooperable with the link to force it in a direction transverse to the plane of the door.

2. In combination with a door member and a door framing member, a link element adapted to be attached to one of said members; an operating element; and a locking device, the latter and said operating element both being adapted to be attached to the other of said members, the locking device being directly cooperable with the link, said operating element having movement in two directions whereby it is adapted to directly disengage the link from the locking device.

3. In a door locking and operating device, the combination with a hasp; of a staple cooperable with the hasp; a locking element cooperable with the staple to lock the hasp thereto; a lever cooperable with the hasp to force it in either direction parallel to the door; and means for forcibly loosening the hasp laterally from the staple.

4. In a device of the character described, the combination with a base plate having a portion thereof adapted to provide a fulcrum bearing surface; of an operating lever mounted on said plate and having an end thereof arranged to fulcrum on said portion; a hasp-staple rigid with said plate; and a locking pin also mounted on said plate.

5. In a device of the character described, the combination with a hasp; of a hasp-staple; an operating lever disposed adjacent said hasp-staple, said lever mounted to swing in a direction parallel to the door and also in a direction transverse thereto whereby, when moved in the last named direction, said lever is adapted to engage the hasp and move it from its staple.

6. In combination with a car having a door opening and door frame, a hasp pivotally attached to the door; a cooperable staple and locking pin mounted on the door frame; an operating lever mounted on the door frame and movable outwardly therefrom, said hasp overlying the lever when the hasp is locked to its staple whereby outward movement of the lever is prevented when the door is locked.

7. In a door locking and operating device, the combination with an operating link having a curved free end; of an operating lever;

and cooperable detachable locking means on said lever and the free end of said link, said means being so located with respect to the support for the lever and point of attachment of the link that the point of detachable connection between the link and lever is substantially in alignment with the point of attachment of the link.

8. In a car having a door opening and a horizontally slideable door, the combination with a hasp pivotally attached to the forward edge of the door, said hasp having an arcuate free end; a lever pivotally mounted on the car side to swing in a plane parallel to the car side; and detachable operating means on the lever and free end of the hasp, said means being so located with respect to the point of support of the lever and point of attachment of the hasp to the door that, in the beginning of the opening movement of the door, the force from the lever is applied substantially in a horizontal line in alignment with the point of attachment to the hasp and door.

9. In a device of the character described, the combination with a hasp; of a hasp-staple; a lever supported intermediate its ends at a point adjacent the staple, one end of said lever providing a handle for manipulating the lever and the end of the lever on the opposite side of the point of support providing a fulcrum for the latter when the latter is moved laterally with respect to the hasp whereby, upon such lateral movement, the lever is adapted to engage the hasp and pry it from the staple.

10. In combination with a door member and a door framing member, an actuating element mounted on one of said members; an operating element mounted on the other of said members; and means for locking said operating element, said operating element, when in locked position, overlying the actuating element and the latter being movable laterally to positively move the operating element from its locked position.

In witness that I claim the foregoing I have hereunto subscribed my name this 29th day of March, 1928.

FRANK DITCHFIELD.
